[57] CLAIM

The ornamental design for a coin storage unit with light, substantially as shown and described.

DESCRIPTION

FIG. 1 is a perspective view of a coin storage unit with light showing our new design;

FIG. 2 is a top plan view thereof;

FIG. 3 is a front elevational view thereof;

FIG. 4 is a right side elevational view, the other side being a mirror image thereof;

FIG. 5 is a rear elevational view thereof;

FIG. 6 is a bottom plan view thereof; and

FIG. 7 is a perspective view with the lid in open position.
